UNITED STATES PATENT OFFICE.

EDWARD A. LANGENBACH, OF CANTON, OHIO.

DESIGN FOR A METALLIC FINISHING-PLATE.

SPECIFICATION forming part of Design No. 23,585, dated August 21, 1894.

Application filed July 16, 1894. Serial No. 517,746. Term of patent 7 years.

To all whom it may concern:

Be it known that I, EDWARD A. LANGENBACH, a citizen of the United States, and a resident of Canton, county of Stark, State of Ohio, have invented and produced a new Design for Metallic Finishing-Plates, of which the following is a full, clear, and exact description, reference being had to the accompanying drawings, making part of this specification.

In the accompanying drawings Figure 1 represents my design for a metallic finishing plate, and Fig. 2, a cross section.

A indicates a representation of a corner piece, and B a juncture piece connecting adjacent panels.

C is a representation of an L piece in the molding that joins the juncture pieces C, that indicate adjacent panels.

D represents a miter piece connecting four of the juncture pieces that indicate four adjacent panels.

The finishing plate as shown, including the corner pieces A, juncture pieces B, L pieces C and miter D, is divided into sub-divisions by series of short broken or intercepted raised ribs or upwardly extended portions a and b, extending along the sides and across the molding on lines at right angles to each other, 30 and rosettes or circular projections c, situated at a point where the ribs a and b would cross if continued, and the open space between the ends of the ribs and the projections or rosettes c.

35 Along the outer edge of the raised portion e of the plate, is formed a raised oval rib h

that passes over the juncture pieces B, and the L pieces C, and terminates in a right angle on the corner piece A. And along the inner edge of the raised portion e is formed a 40 raised oval rib h', parallel to the rib h, on the opposite side that terminate in the representation of a quarter circle k, on the corner piece A, L piece C, and miter D, leaving a plane flat space, between the ribs. 45

The leading features of my design, are a finishing plate divided into sub-divisions by series of short broken or intercepted ribs a, b, 50 extending along the sides and across the plate on lines at right angle to each other, and rosettes or projections situated at a point, when the lines would cross if continued, and further ornamented by the raised central portion e, and oval ribs h h'. The corner piece ornamented by the representation of short intercepted raised ribs and rosettes, the right angle and the quarter circle ribs. The L piece ornamented by the short intercepted raised ribs, the rosettes, the cross rib h and the quarter circle ribs. The miter piece ornamented by the short intercepted ribs, the rosettes, and the quarter circle ribs. 55

What I claim is—

The design for a finishing plate, substantially as herein shown and described. 65

In testimony whereof I have hereunto set my hand this 6th day of July, A. D. 1894.

EDWARD A. LANGENBACH.
